UNITED STATES PATENT OFFICE.

JAMES W. GEORGE AND JESSE H. SCOTT, OF DOWNS, KANSAS.

GRAIN-DOOR FOR CARS.

SPECIFICATION forming part of Letters Patent No. 665,205, dated January 1, 1901.

Application filed April 5, 1900. Serial No. 11,602. (No model.)

To all whom it may concern:

Be it known that we, JAMES W. GEORGE and JESSE H. SCOTT, citizens of the United States, and residents of Downs, Osborne county, Kansas, have invented a new and useful Grain-Door for Cars, of which the following is a specification.

Our invention relates to grain-doors for cars; and our object is to produce a grain-door of simple, strong, durable, and cheap construction which can be easily and quickly secured in or removed from position.

With this object in view the invention consists in certain novel and peculiar features of construction and combinations of parts, as will be hereinafter described and claimed, and in order that the invention may be fully understood reference is to be had to the accompanying drawings, in which—

Figure 1 is a vertical longitudinal section showing the inner side of the grain-door. Fig. 2 is a horizontal section taken above the door and on a larger scale than Fig. 1. Fig. 3 is an exterior view of the car on the same scale as Fig. 1.

Referring to the drawings in detail, where like reference-numerals designate corresponding parts, 1 designates a car of the usual or any preferred type, and 2 the standards at opposite sides of the usual door-opening 3. Secured to the inner sides of the standards 2 are strips 4, having their inner edges 5 tapering inward and downward and forming between the inner faces of the standards 35 and the flange-strips 6 downwardly-converging grooves to receive the door, as hereinafter explained, one of the strips 6 extending, preferably, the full height of strips 4 and the other only about a foot above the floor of the car, as shown in Fig. 1.

The door comprises two sections 7 8, the latter being considerably wider than the former, the meeting edges of the two being hinged together, as shown at 9, and secured to said sections, near their lower edge, is a flexible strip 10, adapted to prevent grain from escaping from the car by working its way under the door. The outer edge of each section tapers downward and inward to correspond with 50 and fit snugly in the tapering grooves formed by standards 2, strips 4, and flange-strips 6,

the arrangement being such that the door as a whole must be raised sufficiently high to clear the short flange-strip 6 in order that it may be conveniently and easily inserted in 55 said grooves and permitted to slide downward until it rests upon the floor of the car, as will be readily understood; or it may be removed by bending it inward along the hinge-joint in order to withdraw its edges 60 from engagement with said grooves, as will be readily understood.

To guard against any accidental inward movement or dislocation of the door, the latch 11, pivoted to the strip 4 above the 65 short flange-strip 6, is provided, said latch being adapted to overlap the inner edge of the door and perform the same function at the upper edge of the door as said flange-strip performs at the lower edge, the downward movement of said latch being limited 70 by lug 12, projecting from the door.

To render the door absolutely rigid by clamping the two sections together in the same plane as though integral, vertical strips 13 and 14 are secured, respectively, to sections 7 and 8 at their outer sides, and bolted or riveted to strips 13 is a V-shaped metallic bar 15, having an opening 16, adapted to fit over the pin 17, secured to one of the strips 14 80 in any suitable manner, this relation of the parts being made permanent by means of a hook 17^a engaging an aperture in pin 17 outward of the V-shaped bar or brace 15, said hook being carried by a chain 17^b, bolted, as 85 at 17^c, to the brace-bar 17^d, said brace-bar increasing the strength and rigidity of section 7 of the door, while the V-shaped bar 15 performs the same function for section 8 of the door. 90

The cams or eccentrics 18, pivoted to the standards 2 above the door, bear upon the upper edge of the latter and prevent upward movement of the same and are adapted to be thrown to an inoperative position, as indicated by the dotted arrows, when it is desired to raise and open the door and remove it from position. When thus arranged and the latch 11 thrown off, it is obvious that by raising the door bodily the height of the short flange-strip 6 it can be easily and quickly withdrawn from the retaining-grooves or as easily re-

placed therein and resecured in such position by restoring latch 11 and cams or eccentrics 18 to the position shown.

The door is connected by a chain 19 with 5 the standard 2, forming the short groove, in conjunction with the short flange-strip 6 and interposed strip 4, and when the door is open it is swung pivotally around with the chained end as a pivot and rests against the inner side 10 of the car in the customary manner.

From the above description it will be apparent that we have produced a break-joint grain-door for cars possessing the features of advantage enumerated as desirable in the 15 statement of invention, and it is to be understood that various changes may be made in its detail construction or arrangement without departing from the spirit and scope or sacrificing any of the advantages of the ap- 20 pended claim.

Having thus described the invention, what we claim as new, and desire to secure by Letters Patent, is—

The combination with a car having the usual 25 door-opening, tapering strips 4, secured to

the standards of the door-opening, flange-strips 6 secured to and projecting inward of the tapering strips, one of the flange-strips equaling the length of the tapering strip and the other extending upward from the bottom 30 of the flange-strips only a short distance, a catch 11, pivoted to the strip 4, above the short flange-strip, a door of tapering form to fit against the tapering strips and between the door-opening standards and the flange- 35 strips, and consisting of two parts hinged together, a lug 12, projecting from one door-section to support the pivoted catch, when engaging the door, and devices carried by the door-opening standards above the door, and 40 bearing down upon the latter, substantially as described.

In testimony whereof we affix our signatures in the presence of two witnesses.

JAS. W. GEORGE.
JESSE H. SCOTT.
